HYDRAULIC POWER UNIT

William Neal Edwards, White Deer, Tex.

Application July 3, 1935, Serial No. 29,749

2 Claims. (Cl. 60—52)

This invention relates to windmills and more particularly to a pump jack, and an object of the invention is to improve over the present type geared windmill and pump jack therefor.

5 In accordance with the present invention hydraulic means is connected between the windmill and the pump rod for operating the latter whereby the pump will have a high maximum of water lifting power.

10 The invention together with its objects and advantages will be best understood from a study of the following description taken in connection with the accompanying drawings wherein

15 Figure 1 is a side elevational view of a windmill embodying the features of the present invention.

Figure 2 is a fragmentary top plan view of the pump jack with certain parts removed.

20 Figure 3 is a horizontal sectional view taken through the pump jack.

Figure 4 is a vertical sectional, elevational view of the power cylinder.

25 Figures 5 and 6 are detail views taken substantially on the lines 5—5 and 6—6 respectively of Figure 2.

Figure 7 is a fragmentary plan view of a valve equipped head plate.

30 Figure 8 is a detail sectional view through one of the pistons of the pump jack.

Figure 9 is a perspective view of a valve operating rod.

35 Figure 10 is an end elevational view of a valve. Figure 11 is a sectional view through the valve. Figure 12 is a plan view of the valve core.

Figure 13 is a schematic view showing the pump, motor, valve and hydraulic circuit.

40 Referring to the drawings by reference numerals it will be seen that 5 indicates generally the tower of a windmill, while 6 indicates generally the wind wheel. The pump rod is indicated by the reference numeral 7.

45 Mounted as at 8 on the tower 5 for rotation in a horizontal plane is a fluid tight casing 9 forming part of the pump jack. A wind vane 11 is rigidly fastened to casing 9 as at 10 to swing the fan fixed into the wind.

50 Mounted in the casing 9 is a cylinder block 12 in the cylinders of which operate the pistons 13. For the block 12 there are provided cover plates 14, and substantially closing one end of the cylinders of the block 12 is a head plate 15. Secured to the head plate is a manifold chamber 16 which together with the head plate 15 are secured in position by suitable bolt means 17.

Provided in the head plate 15 for each of the

cylinders, and connecting each cylinder with the chamber 16 is a port 18 which at one end is formed to provide a valve seat 19. Suitably secured within the port 18 is a spider 20 through the hub of which operates the stem of a poppet valve 21. A suitable spring device 22 is provided for normally retaining the valve 21 engaged with its seat 19.

5 Each of the pistons 13 in its head is provided, as shown in Figure 8 with a port 23 formed at one end to provide a seat for a poppet valve 24. Valve 24 is provided with a stem and operates through the hub of a guide spider 25 and a spring device 26 serves to normally retain the valve 24 in seated position.

10 The pistons 13 are provided with connecting rods 27 that at one end are provided with bearings 28 embracing eccentric disks 29 on a shaft 30. (See Figures 2 and 5.)

15 The shaft 30 is journaled in bearings 31', 32 provided on opposite sides of the casing or housing 9 as shown in Figure 2 and on one end of this shaft is mounted the wind wheel 6.

20 From the above it will be seen that oil within the casing 9 will, on the outward strokes of the pistons 13, pass inwardly through the open ends of the cylinders of the block 12. As the pistons 13 move outwardly on the intake strokes, valve 24 moves to open position so that the oil flows through the pistons. On the return pressure 25 strokes of the pistons, valves 24 close and the oil under pressure is forced through the passages 18, valves 21 opening to permit the oil to pass into the chamber 16.

25 From the chamber 16 the oil under pressure is delivered through a pipe 31 and into the casing of valve 32 through the port 33 on the casing and with which the pipe 31 is connected.

30 In a manner hereinafter more fully set out the oil under pressure is delivered through the valve 32 to a vertical power cylinder 34 to reciprocate the piston 35 operating within said cylinder 34. The piston 35 is provided with a rod 36 which through the medium of a suitable coupling (not shown) is connected with the pump rod 7 for 40 operating the pump. The cylinder 34 is supported on a suitable standard 37 within the casing 9.

35 Arranged in the casing of the aforementioned valve 32 is a valve core 38 provided with through ports 39 and 40 respectively having flared ends 39a and 40a respectively.

40 The valve casing 32 is also provided with ports 41, 42 and a manifold chamber 43 equipped with a port 44.

As best shown in Figure 4, port 41 is connected with the cylinder 34 at the bottom of the cylinder through the medium of a suitable conduit or piping 45. Port 42 is connected with the cylinder 34 adjacent the top of the cylinder through the medium of a suitable piping or conduit 46. Connected with the port 44 is an exhaust or return pipe 47 through which the oil returns to the casing 9. The hydraulic circuit is schematically represented in Fig. 13.

From the above it will be apparent that when port 38 is in registry with ports 33 and 41 the oil pumped from the chamber 16 will pass through the valve and the conduit 45 into the cylinder 34 below the piston 35 to raise the piston. When the core 38 has been rotated in the manner hereinafter set out and passage 48 is in registry with ports 33 and 42 the pumped oil will pass through the valve and the conduit 46 into the cylinder 34 above the piston 35 to cause a downward movement of the piston.

In connection with the above and as clearly shown in Figure 4, when for example, the piston 35 is on its upstroke, oil in the cylinder 34 above the piston will be forced from the cylinder 34 through the conduit 46, port 42, and the valve core 38 being in the position shown in Figure 11, the oil will pass from the valve into the chamber 48 thereof, and from this chamber through port 44 and the conduit 47 back into the casing 9. Thus the oil is continuously being used over and over again. Also, the oil will serve to lubricate the working parts of the device.

For automatically operating the valve there is provided a valve rod 48 that is connected with the piston rod 36 at one end as at 49. The rod or lever 48 is provided with an elongated slot 50 through which extends one end of a crank arm 51 secured to the stem 38a of the valve core 38 and as shown in Figure 10; the other end of the arm 51 operates between a pair of properly arranged stops 52 provided on one end of the valve casing. For releasably retaining the valve 38 in either of its two positions there are provided suitable spring devices 53 as shown in Figure 10 which are pivoted at the outer end to the valve casing and secured at the inner end to lateral projections on opposite sides of the axis of the arm whereby when the springs are off dead center they will move the arm with a snap action against either one or the other of the stops 52 depending upon the direction in which the arm is initially moved by the rod 48.

From the above it will be seen that as, for example, the piston 35 moves upwardly, the lower end of the slot 50 will engage the crank arm 51 of the valve and swing the same from the full line to the dotted line position suggested in Figure 4 thus closing off passage 38 and moving passage 48 into registry with the ports 33 and 42 as the piston 35 reaches the limit of its upstroke. With the port 48 in registry with the ports 33

and 42 the oil will then flow to the top of the cylinder 34 to act on the piston 35 to cause a downward movement thereof. As the piston 35 completes its downward movement the upper end of the slot 50 engages the arm 51 moving the same from the dotted line position in Figure 4 to the full line position shown in said figure and thus places the valve core 38 in the position shown in Figure 11 so that the cycle of operation may be repeated.

For cushioning the downward stroke of the piston 35 there is suitably connected with the cylinder 34 an air bulb or "anti-knock" device 54.

It is thought that a clear understanding of the operation, construction and utility and advantages of the invention will be had from the above, and that I have provided a positive and efficient hydraulic means for driving a pump from a wind wheel.

Having thus described the invention, what is claimed as new is:

1. A hydraulic transmission comprising a substantially closed liquid tight oil supply casing mounted to turn upon a vertical axis, a rotatable shaft within and adjacent one end of said casing and extending crosswise thereof and through a side wall of the casing for connection with a prime mover, a plurality of longitudinally extending fluid pressure pump units of the reciprocating piston type disposed adjacent the opposite end of the casing and opened at their respective inner ends to the liquid of the casing, a common discharge manifold for said pump units at the outer end thereof, means operatively connecting said pump units with the rotatable shaft for operating said units upon rotation of the shaft, a fluid pressure operated motor of the reciprocating piston type extending vertically and centrally of the casing between said shaft and said pump units and concentrically with the vertical axis of the casing, and a hydraulic transmission circuit between said fluid pressure motor, manifold and oil supply casing.

2. A hydraulic power unit comprising a substantially closed liquid-tight oil supply casing, a rotatable shaft within and adjacent one end of the casing and adapted for connection with a prime mover, a fluid pressure pump of the reciprocating piston type disposed adjacent the opposite end of the casing and opened at its inner end to the liquid of the casing, a discharge manifold for said pump unit at the outer end thereof, connection means between said shaft and pump unit for operating the latter by movement of the shaft, a fluid pressure operated motor of the reciprocating piston type extending vertically of the casing between said shaft and pump unit, and a hydraulic transmission circuit between the said fluid pressure motor, manifold, and oil supply casing.

WILLIAM N. EDWARDS.
